UNITED STATES PATENT OFFICE.

MILES H. MANN, OF TERRE HAUTE, INDIANA, ASSIGNEE TO INTERNATIONAL MONEY MACHINE COMPANY, OF TERRE HAUTE, INDIANA.

LISTING-MACHINE.

1,255,198.

Specification of Letters Patent.

Patented Feb. 5, 1918.

Application filed December 13, 1915. Serial No. 66,606.

To all whom it may concern:

Be it known that I, MILES H. MANN, a citizen of the United States, residing at Terre Haute, in the county of Vigo and State of Indiana, have invented certain new and useful Improvements in Listing-Machines, of which the following is a specification.

This invention has to do with listing mechanisms, especially such as are commonly a part of adding machines, and wherein the listing or printing instrumentalities include type carriers that are positioned at the printing point initial to the actual printing or impression taking operation.

It is well known that in the operation of printing devices of the class referred to, the adjustment of the type carriers being differentially controlled by stops and intermediate moving parts, is often inaccurate, due to imperfections in manufacture of such stops and associated parts, wear incident to long use; or other unavoidable causes. Owing to the above condition alinement of the types by which the numerical items, and accompanying characterizations if the latter are used, is exceedingly difficult to secure.

The present improvements involve the provision of special instrumentalities designed to coact with the type carriers whereby to insure the desired alinement of the same before the printing action takes place, and the invention is peculiarly characterized in that after the type carriers operated to effect the desired listing are moved for printing adjustment, they are all given a slight but positive return movement by an alining device so as to accurately position them at the printing point in a manner such that they are held substantially independent of their actuating connections while the impression of the types is being made.

A feature of importance of this invention also resides in the employment of a governor operatively connected with the actuating parts for the type alining device to maintain uniformity of time of operation of said device in relation to the associated principal mechanisms of the adding and listing machine to which the invention is adapted. No liability of untimely operation of the alining means arises therefore and where

the machine in which this alining mechanism is incorporated is already supplied with governor control mechanism, the latter may be availed of for co-action with the said alining means, and the use of a separate governor avoided.

This invention also resides in divers other specific features of construction and combination of parts, all of which will be more fully set forth hereinafter, and in the accompanying drawings wherein:

Figure 1 is a top plan view of an adding and listing machine of the type to which the alining mechanism is especially applicable.

Fig. 2 is a sectional view taken about on the line 2—2 of Fig. 1, or just about inside of the right frame of the machine.

Fig. 3 is a section on the line 3—3 of Fig. 1, and showing more particularly indexing mechanism.

Fig. 4 is a fragmentary sectional view taken about on the line 4—4 of Fig. 5, looking downward.

Fig. 5 is a view in elevation partly broken away and showing more particularly the various parts of the alining mechanism.

Fig. 6 is a sectional view taken about on the line 6—6 of Fig. 4.

Fig. 7 is a fragmentary perspective view bringing out more clearly the guiding means for the type carriers.

General operating and controlling mechanism.

The adding and listing machine illustrated in the drawings is of the type utilizing the customary amount keys 29 arranged in rows of nine each, together with suitable special keys for "repeat", "error", "subtotal", "total" and "non-add" controlling operations. As seen in Figs. 1 and 2, the main actuator is a handle 501 and main actuating shaft 625. The accumulator A is located at the front portion of the machine and the printing or listing mechanism B at the rear portion. On the main shaft 625 is carried the cam sector 502 having the flexible connection 509 with the control lever 508 which is fixed to the governor shaft 626. The movement of the shaft 625 by the handle 501 is designed to rock the sector 502 back and forth, correspondingly rock

the control lever 508, and shift the wipe pawl 511 at the upper end of said lever into special coöperative engagements with the three-armed lever 316 whereby the latter 5 lever is adapted to move the adding pinions of the accumulator A into and out of engagement with respect to the adding racks 301. For this purpose the link 328 connects the three-armed lever 316 with the frame of 10 the accumulator A. The coöperation between the adding pinions of the accumulator and the adding racks 301 is varied in accordance with the well known principle of operation of adding machines, whereby to 15 obtain ordinary accumulation of items, sub-totals, totals, or the elimination entirely of the accumulating action. These phases of the operation of the machine are immaterial to the invention and are therefore not 20 described in detail.

It is noted, however, that the adding racks 301 have connection at their lower ends with the front ends of operating levers 500 which are loosely mounted on the shaft 625, 25 provided with depending arms 500' attached to springs 616 that normally tend to move the levers 500 downward at their front ends and upward at their rear ends. The rear ends of the levers 500 are connected with 30 type carriers 706, as seen in Figs. 2 and 3 especially, and movement of the levers 500 will therefore cause opposite movement of the racks 301 and carriers 706 attached thereto.

35 Normally the levers 500 are maintained in the positions shown in Fig. 2 by a detent bail which consists of a cross piece 505^a and side arms 505. The arms 505 are formed with crooked slots in which are adapted to 40 operate rollers 626' on the lower ends of arms 627 which latter are fixed to the governor shaft 626 to rock with the latter. The cross bar 505^a of the detent bail engages over the rear end portions of the levers 500 and 45 said levers are maintained in their normal positions by said bar until operation of the main shaft 625 rocks said shaft, the sector 502, the control lever 508 and the arms 627, whereupon at a certain period in the movement of these parts the detent bail is raised 50 and the levers 500 are adapted to be rocked or tilted by their springs 616.

Indexing and listing mechanism.

55 The tilting movement of the levers 500 is controlled by the keyboard mechanism including the keys 27 and suitable indexing stops 110, one provided for each key 29, and those for each row of keys being superposed. 60 Depression of a key 29 of a certain row forces rearwardly, by means of a pin 29', the locking bar 302, disengages the front end of said bar from a projection 301' on the coacting rack 301, and simultaneously 65 projects forward an indexing stop 110 into

the path of said projection 301'. According to whichever stop 110 is rendered operative, so will be the degree of movement of the adding rack 301 and lever 500 controlled by said stop. In this way differential movement of each lever 500 is controlled so as to cause one or more increments of movement of the adding pinion of the associated adding wheel and corresponding movement of the type carrier to position a type of the 75 latter at the printing point.

The listing mechanism is not of itself a special feature of the present invention, the same, however, including the types 726 on the carriers 706, and hammers 700 to impinge against the types positioned at the printing point, said hammers being restrained normally by triggers 702 engaging catches 868 on suitable drivers. The means to release or fire the hammers may be of 85 any conventional sort.

The several type carriers 706 operate vertically, being supported for sliding movement by an upper transverse guide rod 845 passing through upper slotted portions of 90 said carriers. At their lower ends the carriers are formed with slots at the front portions of which are provided the teeth 706^a, the rear walls of the slots being straight to coact with the lower guide member 1 which 95 is a plate formed with teeth engaging between the several carriers to maintain the same properly spaced, a cap plate 2 being utilized to retain the carriers against lateral displacement from their operative engagement with the member 1.

The type alining mechanism.

Having in view the foregoing description, it must be apparent that the positioning of 105 the type carriers 706 so that the types to be printed are in alinement, in the absence of special provision being made, depends upon the complete accuracy in the formation of the coöperating stops 110 and projections 110 301 respectively, the latter upon the adding racks 301; also upon the connections between the levers 500 and the adding racks and type carriers, as well as the mounting of the types themselves. In practice it is 115 found almost impossible to secure such accuracy of construction of all these connections to obtain a desired alinement of the number or character types 726, as the case may be. By this invention it is proposed, 120 therefore, to obtain the initial positioning of the type carriers, differentially controlled, by the usual operation and construction of parts as hereinbefore set forth, but in addition to this to effect after such positioning a 125 final readjustment of the carriers by way of a reversing movement by which the latter are positioned by a directly coöperative part or alining device proper. The readjustment is actually a reverse movement of the type 130

carriers to that incident to their original positioning and causes the carriers to be held practically independently of those devices by which the preliminary printing adjustment is secured.

The type alining mechanism is best seen in Figs. 4, 5 and 6 of the drawings, and referring to Figs. 3 and 5 it will be seen that there is located coöperative with the 10 main shaft 625 a drag bar 14 slotted at its front end to engage with the shaft and provided with a pin 13 operating in the space between projections 12' of a rocker member 12 fixed to said shaft 625. At its rear end 15 the bar 14 is slotted at 14' and flexibly connected by the spring 15 attached to studs 16 and 17 on the bar 14 and an arm 10, with an operating device for the alining means. Said operating device includes not only the 20 arm 10 but also the arm 11 (see Fig. 4), these arms being carried by a shaft 7 mounted in the side frames of the machine. The arms 10 and 11 are provided with studs 18 projecting inwardly therefrom and engaging 25 with vertical slots of operating levers 5 which are pivoted at their lower ends at 19 on the side plates 705 forming the frame in which the listing instrumentalities are mounted. Obviously therefore, movement 30 of the operating device comprising the arms 10 and 11 is adapted to impart corresponding slight tilting movement to the levers 5. The levers 5 directly control the operation 35 of the alining device proper, which device consists of a bail seen best in Fig. 6. The bail comprises the side arms 4 and the alining bar 3, the latter adapted to engage with selected ones of a plurality of teeth 706^a formed at the front edge of slotted portions 40 provided in the lower ends of the type carriers. The teeth 706^a are spaced apart in a manner corresponding with the spacing 45 of the types 726 of each type carrier. The levers 5 have two controlling connections with the alining device. In the 50 first place said levers which are held normally at the rearward limit of their movement are provided with stops 20 projecting inward therefrom through slots 705^a in the frame plates 705, said plates engaging with the front edge portions of the side arms 4 of the alining bail and holding said bail in the position shown in Fig. 6 in opposition to the tendency of springs 23 connected with 55 the lower ends of the arms 4, to move the bail forward into engagement with the teeth 706^a. In the above way the levers 5 control the lateral movement of the alining bail by which it engages with the type carriers. The levers 5 furthermore are provided at 60 their upper ends with crooked slots 5' receiving rollers carried by the upper ends of the arms 4 of the alining bail, the formation of the slots 5' being such that during initial 65 movement forward of the levers 5, under

the action of the operating device therefor, including the arms 10 and 11, the stops 20 are carried forward and permit the springs 23 to engage the alining bar 3 with the teeth 706^a preliminarily adjusted by the operation 70 of the general mechanism of the machine, to a position in front of said bar. The final portion of the movement of the levers 5 causes the lower rear ends of the slots 5' to engage the rollers 22 and slightly depress 75 said rollers in such a manner as to carry downward the alining device which has now been engaged with the type carriers. This slight final movement of the alining device causes the bar 3 to engage with the 80 upper straight surfaces of the teeth 706^a and imparts a slight downward movement to all of the preliminarily adjusted type carriers sufficient to bring the types to be alined to the printing point opposite the platen D 85 at which printing point the types are accurately alined and held during the impingement action of the hammers 700. On the return movement of the operating device for the levers 5 the latter move rearwardly, 90 initially raise the alining device, and finally the stops 20 engage the arms 4 and shift the alining device outward from the path of movement of the teeth 706^a.

It is to be noted that the rollers 22 co- 95 operating with the levers 5 are carried by studs 21 (see Fig. 4) which pass through short vertical slots in the frame plates 705.

The actuation of the operating device for the alining means is of course controlled 100 from the main shaft 625, the drag bar 14 being shifted forward incident to the engagement of the rear lug 12' of the rocker member 12 with the pin 13, and rearward by the corresponding engagement of the 105 forward lug 12' with said pin 13.

The springs 23 are comparatively light springs, such only being required because the bar 3 swings into its operative engagement with the type carriers 706. Necessarily the lighter the springs 23 the better 110 since the alining device is returned to normal incident to the return of the levers 500 and connected parts to normal under the action of main restoring springs. 115

The governor mechanism.

Reference has been previously made to the governor shaft 626. As seen in Fig. 6 this shaft has an arm 60 provided with a stud 120 60' engaging the bifurcation of an arm 61 fixed on the shaft 1071. The shaft 1071 is connected in any suitable manner as by arms 516 with the plunger of a dash pot 663 which forms a governor for controlling uniform movement of the various operating parts of the machine irrespective of how quickly the main shaft 625 may be operated by the handle 501. It is to be understood that every time the main shaft 625 is rocked 125 130

the governor shaft 626 and connecting parts 60, 61 and 516 are actuated as controlled by the dash pot 663.

It is proposed according to this invention 5 to utilize the governor mechanism above mentioned in coöperation with the alining means, whereby to coördinate the operation of the alining mechanism with the other principal mechanisms of the machine, and 10 assuring, of course, as well the proper preliminary adjustment of the type carriers before the alining adjustment is effected.

With the foregoing in view, as seen in Figs. 4 and 5 the governor shaft 626 is provided 15 with a governor cam 8 formed with a notched out extremity, and operating in engagement with a roller 9 carried by the arm 10 of the operating device for the alining means. By reason of the provision of 20 the cam 8 it will be observed that the operating arms 10 and 11 cannot move forward to actuate the levers 5 until the cam 8 has been sufficiently rotated in the direction of the arrow to bring its notched portion opposite 25 the roller 9. Notwithstanding, therefore, that the shaft 625 may be moved so quickly as to shift the drag bar 14 faster than required or necessary, the flexible connection 15 permits the cam 8 to retard the 30 movement of the operating arms 10 and 11 until the other mechanisms of the machine have been properly operated to make timely the alining action of the alining device.

It is to be noted that the present invention 35 is not intended to be limited to the application of the principle of operation of the alining means hereinbefore set forth in regard merely to type carriers. The type carriers as described herein and intended to be 40 covered in the claims constitute, broadly speaking, accounting devices and should be considered such in recognizing the scope of the claims annexed hereto. Obviously the alining mechanism of the invention is as 45 advantageous for use in connection with other registering, accounting, and equivalent parts that require alinement, as with type carriers.

Having thus described the invention, what 50 is claimed as new is:—

1. In an accounting machine, the combination of accounting mechanism including accounting devices, controlling connections for moving selected of said devices to carry 55 the same toward predetermined operating positions for preliminary adjustment, means to intentionally readjust all of said selected carriers to final operating position, and means to prevent action of the last means 60 until said preliminary adjustment is completed.

2. In a listing machine, the combination of printing mechanism including a platen, type carriers, controlling connections for 65 moving said carriers to carry their types se-

lected for printing beyond the printing point opposite the platen, and alining means to reverse the movement of the said carriers after said preliminary movement whereby to finally position the same for the 70 printing action.

3. In an accounting machine, the combination of accounting devices, controlling connections for moving said devices toward predetermined operating positions for a 75 preliminary adjustment thereof, an alining member engageable with said devices, resilient means to move the alining member into engagement with the said devices, an operating device coacting with the alining member to restrain the same during the preliminary adjustment of said accumulating devices, and means to actuate the operating device to permit engagement of the alining member with the accounting devices and to 80 then effect longitudinal movement of said alining member whereby to cause a corresponding final alining adjustment of the accounting devices in operating positions.

4. In a machine of the class described, the combination of printing mechanism including type carriers, means for moving the carriers to preliminary positions, stops to differentially control the action of the last mentioned means and correspondingly control the said positioning of the carriers, alining teeth provided on the carriers, an alining device coöperative with said teeth, and means to move said device laterally and longitudinally to cause alining action of the 90 same in respect to the carriers.

5. In a machine of the class described, the combination of printing mechanism including type carriers, means for moving the carriers to preliminary positions, stops to differentially control the action of the last mentioned means and correspondingly control the said positioning of the carriers, alining teeth provided on the carriers, an alining bail coöperative with said teeth, 100 means to engage the bail with the teeth, and an operating device for the bail comprising stops for normally holding the same out of engagement with the teeth and comprising means for shifting the bail after it has been 110 engaged with the teeth.

6. In a machine of the class described, the combination of printing mechanism including type carriers, means for moving the carriers to preliminary printing positions, stops to differentially control the action of the last mentioned means and correspondingly control the said positioning of the carriers, alining teeth provided on the carriers, an alining device coöperative with the teeth of the 115 carriers, spring means to cause engagement of said device with the teeth, an operating device controlling the action of the alining device and comprising stops normally holding the alining device out of engagement 120 125 130

with the teeth, and means to move said stops to permit engagement of the alining device with the teeth, and to impart separate movement to the alining device to cause alining action thereof in respect to the carriers.

7. In a machine of the class described, the combination of type carriers, means for differentially operating the same to move the carriers for preliminary adjustment, an alining device associated with said carriers, and means for operating said device to cause an intentional final reverse movement of the carriers after they have reached their preliminary adjustment, whereby to accurately 15 aline the carriers at the printing point.

8. In a machine of the class described, the combination of type carriers, means for differentially operating the same to move the carriers for preliminary printing adjustment, a main actuator coacting with said parts, an alining device coöperative with the carriers and comprising a pivotally supported member, and operating means separate from said main actuator for operating 25 said member including levers, and roller and slot connections intermediate the levers and the alining device for shifting the latter when in coöperation with the carriers.

9. In combination, a plurality of slidable 30 type carriers provided with teeth, means for differentially moving said carriers for preliminary printing adjustment, and alining mechanism for said carriers including a pivoted alining bail, levers coöperating to hold 35 said bail in an inactive position, means to cause engagement of the bail with the teeth of the carriers, operating arms for shifting the levers to permit the bail to assume an operative position in relation to the teeth of 40 the carriers, and means intermediate the levers and the bail to then move the bail bodily to cause alining action of the same 45 on the teeth of the carriers.

10. In a listing machine, the combination 45 of printing mechanism including type carriers, controlling connections for moving said carriers toward a predetermined printing point for preliminary printing adjustment, an alining device for effecting a final 50 alining readjustment of said carriers, an operating device for said alining device, and a governor adapted to prevent the action of the operating device on said alining device until after completion of the preliminary 55 adjustment of the carriers.

11. In a listing machine, the combination 60 of printing mechanism including type carriers, controlling connections for moving said carriers toward a predetermined printing point for preliminary printing adjustment, an alining device for effecting a final 65 alining readjustment of said carriers, an operating device for said alining device, a governor adapted to prevent the action of 70 the operating device on said alining device.

until after completion of the preliminary adjustment of the carriers, operating means for the said controlling connections, and connections intermediate said operating means and the governor whereby the operating 70 means is likewise controlled by the governor, and a main actuator coacting with the said controlling connections.

12. In a listing machine, the combination 75 of printing mechanism including type carriers, controlling connections for moving said carriers toward a predetermined printing point for preliminary printing adjustment, an alining device coöperative with the carriers to effect a final alining readjustment of the same, a main actuator controlling the operation of said controlling connections, and a retarding governor coacting with the alining device to prevent its operation before the operation of the controlling 80 connections is completed.

13. In a listing machine, the combination 85 of printing mechanism including type carriers, controlling connections for moving said carriers toward a predetermined printing point for preliminary printing adjustment, an alining device coöperative with the carriers to effect a final alining readjustment of the same, a main actuator controlling the operation of said controlling connections, a retarding governor coacting with 90 the alining device, and connections intermediate said governor and the main actuator.

14. In combination, listing mechanism including type carriers, operating means for 100 said type carriers, a main actuator controlling said operating means, a governor coöperative with the listing mechanism to control the speed of operation of said mechanism, alining mechanism for the type carriers including an alining device directly 105 coacting therewith, means to engage said device with the type carriers and shift said device to effect final alining movement of the carriers, and a controlling connection 110 intermediate the last mentioned means and the governor.

15. In combination, listing mechanism including type carriers, operating means for 115 said type carriers, a main actuator controlling said operating means, a governor coöperative with the listing mechanism to control the speed of operation of said mechanism, alining mechanism for the type carriers including an alining device directly 120 coacting therewith, means to engage said device with the type carriers and shift said device to effect final alining movement of the carriers, a controlling connection intermediate the last mentioned means and the 125 governor, and an operating connection intermediate the main actuator and said alining device.

16. In combination, listing mechanism including type carriers, means controlling dif- 130

- ferential positioning of the latter, a main actuator governing the operation of said carriers, an alining device adapted to directly engage the carriers to aline the same, and 5 separate controlling parts intermediate the main actuator and the carriers and alining device for effecting initial movement of the carriers in one direction for preliminary printing adjustment and for then shifting 10 the alining device in a direction to impart reverse movement to the carriers to finally aline the same for printing. 55
17. In combination, listing mechanism including type carriers, means controlling differential positioning of the latter, a main actuator governing the operation of said carriers, an alining device adapted to directly engage the carriers to aline the same, controlling parts intermediate the carriers and 15 the main actuator for causing initial printing adjustment of the carriers, and operating means intermediate the alining device and the main actuator for effecting final alined 20 adjustment of the carriers and comprising levers for shifting the alining device, operating arms connected with said levers, a drag 25 bar connecting said operating arms with the main actuator, a rocker member on the main actuator for shifting said drag bar in opposite directions, and a connection between one 30 of said arms and the drag bar. 65
18. In combination, listing mechanism including type carriers, means controlling differential positioning of the latter, a main actuator governing the operation of said carriers, an alining device adapted to directly engage the carriers to aline the same, controlling parts intermediate the carriers and the main actuator for causing initial 35 printing adjustment of the carriers, and operating means intermediate the alining device and the main actuator for effecting final alined 40 adjustment of the carriers and comprising levers for shifting the alining device, operating arms connected with said levers, a drag bar connecting said operating arms with the main actuator, a rocker member 45 on the main actuator for shifting said drag bar in opposite directions, a flexible connection between one of said arms and said drag 50 bar, a retarding governor, and a governor cam connected with said governor and coöperating with one of the arms to uniformly retard the action of the same irrespective of the speed of operation of the main actuator. 55
19. In a listing machine, the combination of printing mechanism including type carriers, means for actuating the same, indexing mechanism to control the differential setting of the carriers to preliminary printing 60 adjustment, an alining device coöperative with the carriers to readjust the same simultaneously to final printing positions in which they are held independently of the previous action thereon of said indexing mechanism, 65 and means to cause the last named means to effect said final adjustment every time the machine is operated. 65
20. In a machine of the class described, the combination of accounting devices, indexing 70 means for controlling said accounting devices in accordance with a predetermined transaction, operating means for the accounting devices adapted to preliminarily move the same toward operating accounting positions, other actuating means to set the accounting devices at final operating positions, an instrumentality for preventing the action of the actuating means last named until completion of the preliminary positioning 75 of the accounting devices by the first mentioned operating means. 80
21. In a machine of the class described, the combination of accounting devices, indexing means for controlling said accounting devices in accordance with a predetermined 85 transaction, operating means for the accounting devices adapted to preliminarily move the same toward operating accounting positions, an actuating member to positively 90 reset all of the accounting devices after the preliminary positioning of the same is completed by said operating means, and an instrumentality coacting with said actuating member to prevent its coöperation with the 95 accounting devices until completion of the said preliminary movement of said devices. 95
- In testimony whereof I affix my signature.
- MILES H. MANN.
